(57) **CLAIM**

The ornamental design for a fireplace, as shown and described.

DESCRIPTION

FIG. 1 is a top view of a fireplace, showing my new design; FIG. 2 is a front view thereof;

FIG. 3 is a side view thereof;

FIG. 4 is top view of a fireplace, shown in a different environment with a vertical stand;

FIG. 5 is a front view thereof;

FIG. 6 is a side view thereof;

FIG. 7 is a top view of a fireplace, shown in a different environment with a suspension rod;

FIG. 8 is a front view thereof;

FIG. 9 is a side view thereof;

FIG. 10 is a top-down perspective view of FIG. 1; and, FIG. 11 is a bottom-up perspective view of FIG. 1.

The broken lines shown in the drawings are for the purpose of illustrating portions of the fireplace that form no part of the claimed design.
